(21) Appl. No.: **29/377,712**

(57) **CLAIM**

I claim the ornamental design for the soap dispenser with integrated digital timer, as shown and described.

(22) Filed: **Oct. 25, 2010**

DESCRIPTION

(51) **LOC (9) Cl.** 23-02

FIG. 1 is a front view of the soap dispenser with integrated digital timer.

(52) **U.S. Cl.** **D6/545**

FIG. 2 is a rear view of the claimed design.

(58) **Field of Classification Search** D6/542-545;

FIG. 3 is a side view of the claimed design.

221/208, 282, 283; 222/105, 173, 180, 181.1,
222/181.2, 181.3; D10/2

FIG. 4 is a top view of the claimed design.

See application file for complete search history.

FIG. 5 is a bottom view of the claimed design; and,

(56) **References Cited**

FIG. 6 is an isometric view of the claimed design.

U.S. PATENT DOCUMENTS

Appearing in FIGS. 1 and 6 are words "Clean", "Counts", "PUSH", and "00:20", which are in dashed lines forming no part of the claimed design.
